UNITED STATES PATENT OFFICE.

ELLEN BRADY, OF BLOOMFIELD, NEW JERSEY, ASSIGNOR TO HENRY BRADY, INC.,
A CORPORATION OF NEW JERSEY.

PACKAGE-WRAPPING DEVICE.

Application filed June 30, 1922. Serial No. 571,975.

My invention relates to improvements in package and bundle wrapping and tying machines, and comprises a bench or table upon which the articles to be bundled or wrapped may be mounted upon wrapping paper and held in position while the wrapping and tying operations are accomplished, the device being disclosed in its preferred form as adapted for use in tying up bundles of pie plates or similar discs.

In the accompanying drawing, I have illustrated a suitable form of device embodying an application of my invention.

2 indicates a cabinet having a top 3 and guides thereon 4-5. 6-7 indicate slides adapted to pass between the guides 4-5 as shown, and upon these are mounted blocks 8-9 carrying brackets 10-11 at the end of which are secured discs 12-13. 14 indicates a channel-shaped holder mounted upon the tops of the guides 4-5 as shown, and allowing for the passage of the discs 12-13 longitudinally thereof.

15-16 indicate levers pivoted at their ends to the slides 6-7 and at their opposite ends to the levers 17-18, the lower ends of which terminate in pedals 19-20, and counterweights 21-22 as shown, the same being mounted upon a shaft 23 so that by stepping upon the pedal 19 the disc 13 is thrust rightwardly and when released returns to its leftward position, while upon depressing the pedal 20 the disc 12 is thrown leftwardly and when released returns to its rightward position, 23' indicating stops for locating the foot. 24-25 indicate partitions for separating the counterweights from the pedals so as to prevent interference in the operation of the foot.

When a package of discs or plates is to be tied, both pedals are depressed by the operator and a sheet of paper is laid across the channel between the discs 12-13 which are free to pass over the sheet and before placing the sheet in position strings or ropes are passed transversely of the channel through the guides 26 so that after the discs or plates have been placed upon the sheet and the same has been folded over the plates forming a tube of paper within the channel

and within which the plates are held by the discs 12-13, one of the discs is now withdrawn by depressing the pedal at its side of the machine, and the paper is folded over that end of the package, after which the disc is released by the foot retaining the folds in position. The same operation is now repeated at the other end of the package, after which the strings are tied around the package in any suitable and convenient manner. 27 indicates a suitable form of hook which may be used for retaining the tying strings in convenient position for use, and 28 indicates a bar or rack over which the sheets of paper may be hung for convenience.

Of course it will be understood that various modifications may be made in the construction and arrangement of parts without departing from the spirit of the invention as claimed.

I claim:

1. In a device of the class described, a bench and a support thereon conforming in part to the shape of the package to be wrapped, channels beneath said support, and holding devices with slides adapted to slide longitudinally within said channels, a pair of bell cranks fulcrumed in said bench and having foot pieces each of which is adapted to slide one of said holding devices, links between the opposite ends of said bell cranks and their respective slides, and counter-balances adapted to normally hold said slides and holding devices in retracted position.

2. In a device of the class described, a bench having opposed fixed sides between which articles are adapted to be wrapped, a pair of movable holders normally projected in the direction of each other and means for releasing said holders independently, said means consisting, for each of said holders, of a bell crank having a pedal at one end and a link connected with its respective slide at the other end, and a counter-balance adapted to normally maintain said respective slide and holder in retracted position.

In testimony whereof I hereunto affix my signature.

ELLEN BRADY.
